UNITED STATES PATENT OFFICE.

JAMES P. WROE, OF LAGRANGE, TEXAS, ASSIGNOR OF ONE-HALF TO GEORGE J. MAUER, OF LAGRANGE, TEXAS.

SADDLETREE-BAR AND STEEL FORK.

No. 895,707.

Specification of Letters Patent.

Patented Aug. 11, 1908.

Application filed October 6, 1906. Serial No. 387,794.

To all whom it may concern:

Be it known that I, JAMES P. WROE, a citizen of the United States, residing at La-
5 grange, in the county of Fayette and State of
Texas, have invented certain new and useful
Improvements in Saddletree-Bars and Steel
Forks; and I do hereby declare the following
to be a full, clear, and exact description of
the invention, such as will enable others
10 skilled in the art to which it appertains to
make and use the same.

This invention relates to saddles, and has
for an object to provide a saddle-tree em-
bodying new and improved elements of con-
15 venience, strength and comfort.

A further object of the invention is to pro-
vide a metallic saddle-fork and improved
means for connecting the saddle-fork to the
bar.

20 A further object of the invention is to pro-
vide a saddle-tree having a bar and an im-
proved metallic fork rigidly connected there-
with and with the gullet portion of the saddle
completed by means of a curved wooden
25 member rigidly connected with the fork.

A further object of the invention is to pro-
vide in a saddle-tree improved adjustable
stirrup-leather securing device.

30 A further object of the invention is to pro-
vide in a saddle a tree having a curvature ar-
ranged to permit the rider to secure himself
firmly upon the said saddle by locking his
legs beneath and into the curvature.

35 A further object of the invention is to pro-
vide a saddle-tree bar so arranged as to hold
the ground seat out of contact with the back
of the animal ridden and permit a current of
air through the saddle at all times.

40 With these and other objects in view, the
invention comprises certain novel construc-
tions, combinations and arrangements of
parts, as will be hereinafter fully described
and claimed.

45 In the drawings:—Figure 1 is a perspective
view of the improved saddle-tree comprising
the bar, the metallic fork and stirrup leather
fastening device. Fig. 2 is a view in front
elevation of the frame portions shown in
50 Fig. 1. Fig. 3 is a vertical sectional view of
the improved saddle-tree frame taken on line
3—3 of Fig. 2. Fig. 4 is a perspective view
of the improved tree member or fork. Fig. 5
is a perspective view of the improved ad-
55 justable stirrup leather securing means.

Like characters of reference designate cor-

responding parts throughout the several
views.

The saddle-tree forming the subject-mat-
ter of this application, comprises spaced bars
10 of substantially the ordinary construc-
60 tion, but preferably formed thicker than
usual to hold the ground seat of saddle out of
contact with the horse's back and at the
same time permit a circulation of air through
the tree and between the raised bars. The
65 bars 10 are connected at their rear ends by
means of the usual curved frame portion 11
provided with a curved opening 13 to arch
over the horse's back.

At the forward end the bars 10 are rigidly
70 secured together by means of the fork 14
shown in perspective in Fig. 4, and comprising
the legs 15 and 16, forming the arched
gullet 17 of the saddle-tree. The fork mem-
ber 14 is provided with reversely inclined
75 portions 18 and 19 arranged to conform sub-
stantially to the inclination of the bars 10
and rigidly secured thereto by means of
staple rivets 20 engaging within notches 21
at the extremities of the legs 15 and 16. The
80 fork 14 is preferably formed of metal and to
provide the desired roll, as 22, without add-
ing undue weight to the saddle-tree is formed
hollow or concave as shown at 23 in Fig. 4.
The fork 14 is also provided with openings 24
85 through which are inserted screws 25 posi-
tioned and proportioned to be inserted into
and engage a gullet portion 26 preferably
formed of wood. The fork is further pro-
vided with a clip bolt 27 having a head 28,
90 which prevents the said clip from being dis-
located relative to the tree and having its end
29 bent over and embracing the gullet mem-
ber 26 and secured, if necessary, by means of
a screw or other fastening 30.

95 The bars 10 are provided with depressions
or indentations 31 arranged and propor-
tioned to accommodate an adjustable stirrup
leather securing means, shown as a whole at
33 and comprising each a semi-flexible me-
100 tallic strap provided with spaced openings as
34 in one part and 35 in the opposite member
and with oppositely disposed openings 36.
The stirrup leather securing device is folded
as at 37 embracing a rigid bar 38 and pro-
105 vided with openings 39 adjacent the said bar
and formed through both members of the
fastening. The fastening device is secured
to embrace the bars 10, and within the de-
pressions 31 as by the rivets or other fasten- 110

ing means 40 and 41, and with the openings 39 and bar 38 disposed at opposite sides of the saddle and below the bars 10.

The fork 14 is continued at its upper end 5 to form the usual pommel 42, and the entire structure, formed as described, is preferably covered with any approved covering sheet, preferably rawhide, in substantially the usual manner, except that the said cover or 10 envelop is sewed near the inner edges of the bars 10 in the position shown at 43, being in such position as not to engage or injure the back of the horse. To further accommodate the stirrup leather fastening device the fork 15 14 is formed adjacent its lower end with a cut-out portion 44, whereby the strap 33 may be disposed further forward upon the bars 10 and somewhat beneath the roll shown at 22. The cut-out portion 44 is also arranged to fit under the ground seat.

It is to be understood that the device shown and described illustrates only the frame-work of a saddle-tree upon which the superstructure is erected and the super- 25 structure may embody any usual and improved form and configuration. It is to be especially noted that the fork 14 is provided with a bulged portion 22 forming the rear- 30 wardly extending roll beneath which the rider may clasp or grip his legs to retain his seat upon the saddle and to prevent being thrown therefrom. The fork composed of metal, as described, is rigidly secured to the bars 10 and designed to provide a tree of the 35 desired and necessary form and to present the necessary strength and rigidity to withstand the strains of riding, roping and all other strains to which the saddle is normally or extraordinarily subjected.

40 The stirrup leather securing device is arranged to be used upon saddles of various sizes and by reason of the spaced registering

openings may embrace and be secured upon bars of various sizes. With the use of the stirrup leather securing means the stirrup 45 leather or strap extends only thereto and is removable therefrom so that in case of breakage or other accident the stirrup leather may be cheaply replaced while the stirrup fastening means provides a device of great 50 strength and economy, saving a very considerable amount of leather in each pair of stirrup leathers and also lessening the labor required to build up the ground seat.

What I claim is:—

1. In a saddle-tree, a stirrup leather fastening device comprising a sheet of semi-flexible material folded upon a rigid bar and provided with registering openings adjacent the bar, and with one end longer than the other 60 and arranged to fold over and upon the shorter end and provided with spaced registering openings adapted to receive fastening means.

2. In a saddle tree, a branched fork embodying rearwardly extending rolls defining hollows in the vertical sides conforming substantially with the rolls.

3. In a saddle tree, a branched fork having rearwardly extending roll portions cut away 70 at the lower end along reversely inclined lines, notched extensions formed upon the ends of the branched fork, and means embracing the notched extensions adapted for securing the tree to the saddle bar.

4. In a saddle tree, a branched fork embodying rearwardly extending roll portions.

In testimony whereof I affix my signature in presence of two witnesses.

JAMES P. WROE.
